BOOKKEEPING MACHINE

Elis Magnus Magnusson, Stockholm, Sweden, assignor, by mesne assignments, to Ekonomregister Inc., New York, N. Y., a corporation of New York

Application July 30, 1938, Serial No. 222,244
In Sweden July 8, 1936

7 Claims. (Cl. 235—60)

This application is a continuation-in-part of application Serial No. 38,475 filed August 29, 1935, and, as to common subject matter, relates back to said application Serial No. 38,475 for all dates and rights incident to the filing thereof and the filing of foreign applications corresponding thereto.

My present invention relates to apparatus and machines for accounting, book-keeping and balancing purposes.

My invention has particular relation to apparatus or machines of this type having a plurality of adding and subtracting totalizers and sometimes also totalizers adapted only for addition; said totalizers being operable in such manner that all those totalizers which are combined in a certain operating cycle of the machine are selected and have their respective sense of calculating operation determined by a single setting member individual to said combination, or by a certain position of a setting member common to several of said combinations, which position is individual to a certain combination.

In known machines of this type subtotaling and totaling of negative amounts contained in a totalizer has not been possible in a single cycle of the machine, this depending on the well-known fact that, as the normal position of the subtracting wheels of such a totalizer is at 9 instead of 0, the amount contained in said subtracting wheels, when the totalizer has passed from positive to negative, is one unit short.

It is an object of my invention to provide an apparatus or machine of the type described permitting in one single operating cycle of the machine the setting of a totalizer to take negative amounts contained in the totalizer and of other totalizers to add or subtract said amounts.

Another object of my invention is to provide an apparatus or machine of the type described permitting setting of a totalizer to take totals by means of one single setting of one single member.

Still another object of my invention is to provide an apparatus or machine of the type described in which means are provided automatically to add a unit to the amount contained in a totalizer, when said amount is negative, said means being controlled by the same setting member which sets the totalizer to take a negative subtotal.

A further object of my invention is to provide an apparatus or machine of the type described

having means controlled by a totalizer or totalizers to render it possible to use the same setting member for totaling or subtotaling the amount of the totalizer irrespective of the totalizer containing a positive or negative amount.

A still further object of my invention is to provide an apparatus or machine of the type described having means preventing a setting member or members from being actuated, when a given totalizer is not in zeroized position.

These and other objects of my invention will be apparent according as the specification proceeds reference being made to the accompanying drawings which form part of this specification and in which a preferred embodiment of the machine is shown.

In the drawings:

Fig. 1 is a plan view of the machine with various details omitted for the sake of clearness;

Fig. 2 is a lateral view of the central section of the machine, the key board being partly broken to show an amount key and three analyzing and totaling keys;

Fig. 3 is a partial front view of the key board;

Fig. 4 is a partial lateral view of the key board showing also an automatic key releasing mechanism in releasing position;

Fig. 5 is a lateral view of the controlling means for totalizer *a*;

Fig. 6 is a lateral view of the means for returning the ten transfer mechanisms into starting position;

Fig. 7 is a perspective view of the connections of a given analyzing key with members selecting a combination of totalizers and controlling the sense of calculation of said selected totalizers;

Fig. 8 is a perspective and purely diagrammatic view of the machine showing the disposition of the eleven totalizers in relation to each other;

Fig. 9 illustrates the connections between the actuator wheels of the central section and those of the lateral sections;

Figs. 10 and 11 are a plan view and a lateral view, respectively, of totalizer *a* in Figs. 1 and 2 on an enlarged scale;

Fig. 12 is a lateral view showing the mechanism for supplying a fugitive one in totalizer *a* for totaling negative amounts;

Fig. 13 is a partial view on an enlarged scale of the mechanism for setting a totaling key compulsory to take a positive or negative total;

Fig. 14 is a partial perspective view of Fig. 11;

Fig. 15 is a partial perspective view of a means for locking a registering key;

Fig. 16 is a partial lateral view of the key board showing part of a releasing mechanism for the actuator slides of the digit keys;

Figs. 17 and 18 are a plan view and a front view, respectively, of said releasing mechanism;

Figs. 19 and 20 are a partial lateral view and a plan view, respectively, of a modified embodiment of said releasing mechanism;

Fig. 21 is a lateral view of the releasing rod of Figs. 19 and 20;

Fig. 22 is a diagram illustrating the mode of operation of the machine in a given example.

Key board

The key board, see especially Fig. 1, comprises thirteen analyzing keys selecting and setting the totalizers to carry out different business transactions, viz. nine keys

A to A
1 to 9

inclusive, for the registration of amounts in the totalizers (registering keys) and four keys

B to B
1 to 4

inclusive, for the taking of totals and subtotals (totaling and subtotaling keys), further four keys

R to R
IV to VII

inclusive, for zeroizing certain of the totalizers, further a plurality of rows of special keys generally designated by C and serving for the registration of the name and the day of the month, and finally a plurality of rows of amount or digit keys generally designated by D.

All of the keys rest each on a vertical rod 21 (see Figs. 2, 3 and 4) actuated by a spring 20 and provided with two pins 22 and 23. All the keys of a row cooperate by their pins 22 with an inclined surface 24 on a stopping plate 25 rotatably mounted on a shaft 26 and actuated by a spring 27. Arranged below said plate 25 is an actuator slide 28 having a shoulder 29 which in starting position of the slide is disposed at a horizontal distance from the edge of the plate 25 corresponding to one tooth for the purpose to be described later on. Further, all the keys of each row cooperate by their pins 23 with hooks 30x on a detent rod 30 suspended in arms 31 fixed on two shafts 32 and 33. The rods 30 are movable in their longitudinal direction by a pin 37 on one of the arms 31 engaging a slot 34 in rod 30. A spring 35 tends to retain the rod 30 in engagement with a stopping bar 36.

By means of a link 60 engaging the lower end of each of the key rods 21, each analyzing key and zeroizing key is connected to an arm 62 secured on a shaft 63 (see also Fig. 7). Fixed on said shaft 63 are arms 64 of a number corresponding to that of the functions to be performed when depressing the key. By means of a wire 65 each of said arms 64 is connected to a lever 66a, 67a, 68a, 69a, 70a or 71a (see Fig. 2 in which the subscript a is given the reference numerals mentioned to indicate that the parts seen in this figure are for a totalizer), said levers being each by link or wire connected with the member to be controlled as will be further described later on.

Automatic key releasing mechanism

Secured to the main driving shaft 50 of the machine is a disk 74 (see Fig. 2 and especially Fig. 75

4) carrying a double-armed lever 77 rotatably mounted on a stud 75 on the disk and actuated by a spring 76 which tends to retain lever 77 in engagement with a stop 78 on disk 74. Cooperating with the end 79 of lever 77 by its hook-shaped arm 81 is a bell-crank lever 84 rotatably mounted on a stud 80, the other arm of said lever 84 being connected by means of a link 86 to the lower end of an arm 87 secured to shaft 32. A spring 85 tends to maintain the lever 84 in starting position with arm 87 in engagement with a stop 88.

The keys are returned into starting position in the following manner. When the main driving shaft 50 is rotated in clockwise direction by the customary actuating mechanism, i. e. a crank or a key-controlled motor, arm 77 is rocked on its stud 75 counter-clockwise from the position shown in Fig. 2 against the action of the spring 76 past bell-crank lever 84 which is not actuated as it is prevented therefrom by stop 88. When arm 77 has passed bell-crank lever 84 spring 76 returns the arm into starting position into engagement with stop 78. On the return stroke of the driving shaft 50 arm 77 with its end 79 strikes the hook-shaped end 81 of bell-crank lever 84 rocking said lever in clockwise direction into the position shown in Fig. 4. By means of link 86 and arm 87 this movement is transmitted to the detent rods 30 causing the pins 23 of the key rods 21 to be brought out of engagement with the hooks 30x of said detent rods and the keys to be returned into starting position by the action of their springs 20. The position of arm 77 and that of bell-crank lever 84 are such as to cause arm 77 to move out of engagement with the hook 81 on its further rotation, the bell-crank lever 84 being returned into starting position by the action of its spring 85.

Actuator mechanism

Rotatably mounted on a common shaft 46 (see Fig. 2) are a plurality of toothed wheels 45, the actuator wheels, each wheel being actuated by a spring 48 secured to a bar 47. Each actuator slide 28 is pivotally connected as at 28¹ to a link 40 which in its turn is connected as at 40¹ to a second link 41 pivoted by means of a pin 42 to the corresponding actuator wheel 45. There is an actuator wheel 45 provided for each of the rows of date and digit keys C and D and, if desired, also for the rows of analyzing and totaling keys A, B, R. Each actuator wheel is connected by means of a double armed lever with a printing type bar, as will be described later on, whereas only such wheels 45 corresponding to the rows of digit keys D are in mesh with and control totalizer wheels.

Secured to the driving shaft 50 is a cam disk 51 (see Figs. 1 and 2), and riding on said cam disk is a roller 52 on an arm 53 rotatably mounted on a stud 54. A spring 58 tends to maintain roller 52 in engagement with disk 51. At its free end arm 53 is pivotally connected to a link 55 which is movable in its longitudinal direction. With its other end link 55 embraces a return rod 56 connecting the lower ends of two arms 57 secured to the shaft 46 of the actuator wheels 45. Rod 56 locks the actuator wheels normally by engaging one of the spokes thereof.

Setting of the actuator by the keys

When depressing a key the pin 22 strikes the inclined surface 24 of the stopping plate 25 moving said plate in counter-clockwise direction as shown in Fig. 3. At the same time pin 23 forces

the detent rod 30 towards the left in Figs. 2 and 4 and engages the corresponding hook 30x thereon, the rod 30 being then returned to starting position by spring 35. In each stopping plate 25 which has not been actuated the edge of the plate serves as stop for the shoulder 29 of the actuator slide 28, whereas pin 22 serves as such a stop, when a key of the corresponding key row has been depressed. When then on starting the machine during the forward stroke the main driving shaft 50 is rotated in clockwise direction, arm 53 and link 55 are moved a full stroke to the left in Fig. 2 under the action of spring 58, causing the actuator wheels 45 to be disengaged from locking rod 56. Under the action of its spring 48 each actuator wheel 45 is then rotated through an angle corresponding to the distance through which the corresponding actuator slide 28 is permitted to move to the left in Figs. 2 and 4, that is to say for a key which has not been actuated, until the shoulder 29 strikes the edge of the corresponding stopping plate 25 and for a key which has been actuated, until said shoulder strikes the corresponding pin 22. During the return stroke of the machine all actuator wheels 45 and, consequently, also the actuator slides 28 are returned into starting position by the action of return rod 56.

As far as a depressed analyzing or zeroizing key is concerned the totalizers are simultaneously conditioned for operation in correspondence to the desired business transaction as will be more fully described later on.

General design of the machine

In the embodiment shown (see Figs. 1 and 8) there are eleven totalizers designated by *a*, *b*, *c*, *d*, *e*, *f*, *g*, *h*, *k*, *l* and *m*, see Fig. 8. Totalizers *a*, *b*, *c*, *d*, *e*, *f* and *g* are adding and subtracting totalizers, whereas totalizers *h*, *k*, *l* and *m* are only adding totalizers. The totalizers are arranged in three sections, the totalizers *a*, *b* and *c* in a central section, totalizers *d*, *e* and *f* in a right-hand section and the other totalizers in a left-hand section (see Fig. 1). In this connection it is to be observed that the number of totalizers may be varied according to the use for which the machine is intended.

The main driving shaft 50, the actuator shaft 46 and the return rod 56 extend through all three sections of the machine. The operating mechanism 51 to 57 of the actuator wheels 45 is arranged at the right hand of the right hand section as shown in Fig. 1. The actuator wheels 45 of each section are common to all totalizers in said section. The actuator wheels of the central section are actuated directly from the keyboard, whereas the actuator wheels of the lateral sections are set by the influence of those of the central section in the following manner (see Figs. 2 and 9).

Permanently in mesh with each actuator wheel 45 of the amount or digit keys D is a pinion 80, 90¹ etc., and those pinions which correspond to actuator wheels of the same denominational order in the three sections are fixed on one and the same shaft 91, 91¹, etc. Consequently, an amount set up on the keyboard and transferred to the actuator wheels of the central section will be compulsorily transferred to the actuator wheels of the lateral sections which, thus, also will be set in accordance with the setting of the keyboard.

The operating shafts 63 of the analyzing and zeroizing keys A, B and R extend at both sides

5 of the central section in front of the lateral sections and carry on said extensions arms 64 each connected by a wire 65 to a lever 66, 67, 68, 69, 70 or 71 connected by link or wire with the control members of the totalizers of said lateral sections.

In Fig. 2 which shows the totalizers *a*, *b* and *c* of the central section only totalizer *a* is shown to be provided with means for supplying the fugitive one and only totalizer *b* is shown to be provided with tens transfer means in order to render the illustration more perspicuous, but it is to be observed that all totalizers are provided with tens transfer means and that all totalizers from which a negative total or subtotal is to be taken are provided with fugitive one supplying means.

In the drawings the different parts of the totalizers as well as the various members controlling same are designated by the same reference numerals with the addition in Figs. 1, 2 and 5 of the letter *a*, *b* etc. which indicate the particular totalizer to which said parts or members belong. In Figs. 10 and 11 which illustrate specifically the totalizer *a* but which may be referred to for the description of any adding and subtracting totalizer, the different parts are designated only by the reference numerals without addition of any letter except for some parts which are characteristic of totalizer *a*.

General design of the totalizers and their tens transfer mechanism

Referring especially to Figs. 10 and 11 each adding and subtracting totalizer comprises two sets of permanently intermeshing toothed wheels 100 and 101. The adding wheels 100 are rotatably mounted on a common spindle 102 and the subtracting wheels 101 are rotatably mounted on a common spindle 103. The adding wheels stand normally at 0, whereas the subtracting wheels 101 normally stand at 9. The spindles 102 and 103 are secured in a common bridge 104 movable in a manner to be described later on so as to bring the totalizer wheels 100 and 101 selectively into and out of engagement with a group of intermediary toothed wheels 170 journaled on a common shaft 169 and permanently in mesh with the actuator wheels 45. In the embodiment shown the ten transfer means of the totalizer is applied to these intermediary wheels 170.

The pairs of totalizers *h*, *k* and *l*, *m* form each a unit equal to an adding and subtracting totalizer with the difference that the wheels of the totalizers of a pair do not mesh with each other.

Each intermediary wheel 170 comprises two halves 171 and 172, one half 171 having conventional teeth and engaging corresponding actuator wheel 45 and the other somewhat thinner half 172 having pointed teeth in order to facilitate their engagement with the totalizer wheels 100, 101. The wheel half 171 has an arc-shaped slot 173 and the wheel half 172 has a pin 174 engaging said slot. The slot 173 has a length corresponding to one tooth. The wheel halves are connected with each other by means of a spring 175 which tends to keep the pin 174 in abutting engagement with the upper edge of the slot 173. Each intermediary wheel 170 is provided with a ten transfer pawl 180 in the form of a bell-crank lever rockable on a shaft 179. The pawl 180 has its one arm 181 shaped to form a trip-nose 182 arranged right below the tooth of the totalizer wheel to be brought into engagement

with the wheel half 172 and cooperating with a transfer tooth 183 provided on said totalizer wheel. The other leg 184 of the ten transfer pawl 180 cooperates through its end 185 with the pin 174 of the wheel half 172 of the next higher order.

Secured to arm 184 is a pin 186 engaging alternately one of two recesses 187 and 188 in a detent lever 190 rockable on a stud 189. A spring 192 connects a projection 191 of the ten transfer pawl 180 with lever 190 and tends to keep the pin 186 on said pawl 180 in engagement with either of the recesses 187 and 188. Secured on a shaft 195 are bell-crank levers 196 and 197. A pin 196x on one arm of the lever 196 is adapted to cooperate with the detent lever 190 and the other arm of the lever 196 with the pin 174.

The bell-crank lever 197 is adapted to be operated from the driving shaft 50 in the following manner (see especially Fig. 6). Journalled on a shaft 142 is a lever 200 maintained in engagement with a stop 199 by a spring 127. Journalled on a stud 201 on one arm of said lever is a double-armed lever 202 which by means of a spring 203 is kept in abutting engagement with a stop 204 provided on lever 200. Lever 202 is adapted to be operated by an arm 122 on a disk 120 secured to the driving shaft 50. The levers 200 and 202 together with appurtenant parts are common to all three totalizers of a section and are arranged at the right-hand side of the section right below a locking mechanism for the totalizers to be described hereinafter. It is to be observed, however, that the above mechanism including levers 200 and 202 may be common to all totalizers of the machine.

The arm of the lever 200 remote from lever 202 is connected with the above-mentioned bell-crank lever 197a of totalizer *a* (see also Fig. 2) by means of a link 205, a bell-crank lever 206 fulcrumed at 206x and a link 207. To the totalizer *b* the movement is transferred from lever 197a by means of a link 310 connecting said lever with the lever 197b. To the totalizer *c* the movement is transmitted from bell-crank lever 206 by means of a link 311 connecting said lever with the bell-crank lever 197c (see also Fig. 6).

The operation of the ten transfer mechanism will be described in connection with the performance of addition in totalizer *a*.

Mechanisms for directing the totalizers for addition, subtraction and positive totaling

As seen in Figs. 1 and 2 and on an enlarged scale in Fig. 6 the disk 120 secured to the main shaft 50 is provided with a peripheral projection 121, and cooperating with said projection is a roller 124 on a locking arm 125 rockable on a stud 126, said roller 124 being normally retained in engagement with the projection by the above said spring 127. Engaging the free end of arm 125 is a link 130 which by means of a bell-crank lever 131 and a link 132 is rotatably connected with a pin 133a on an arm 134a secured to a shaft 106a. Pin 133a projects somewhat beyond a double-armed lever 105a rockable on the shaft 106a and normally locked by said pin 133a.

The corresponding arm 134b of the totalizer *b* (see Fig. 2) is connected with arm 134a by means of a link 312 and arm 134c of totalizer *c* is connected with arm 134b by means of a link 313 and a bell-crank lever 314.

The locking mechanism above described is common to all of the three totalizers of the central section and a similar mechanism is pro-

vided also for each of the lateral sections, the mechanism being arranged at the right-hand side of the corresponding section as seen in Fig. 1. In addition to said common control means the setting of each totalizer for addition or subtraction or totaling is controlled in the following manner (see Fig. 2).

One of the arms of the bridge 104a in which the totalizer *a* is mounted is at its free end as at 108a pivotally connected to one arm of the double-armed lever 105a actuated by a spring 107a which tends to swing the lever in counter-clockwise direction in Fig. 2. The other arm of the lever 105a is locked by a pawl 110a retained in locking position by a spring 111a and connected by means of a link 112a with a bell-crank lever 68a operable by the analyzing keys.

The spindle 102a projects somewhat beyond the bridge 104a and rests on one arm of an angular catch 114a rockable on a stud 113a and retained in engagement with the spindle 102a by a spring 116a. The other arm of the catch is, by a link 115a, connected to a bell-crank lever 61a operable by the analyzing keys.

With its free end 135a bridge 104a rests on a stud 136a on the end of an arm 138a rockable on a stud 137a (see also Fig. 11). Pivot to the stud 136a is a link 140a which at its other end (see especially Fig. 5) is pivot to the end of one arm 141a of an Y-shaped lever 143a rotatable about the shaft 142, the other arms of said lever being designated by 144a and 145a.

For each totalizer *a*, *b* and *c* there is provided one such Y-shaped element 143 with appurtenant parts to be now described. The totalizer *b* is connected by its Y-shaped element 143b by means of an arm 138b (see Fig. 2) fixed to the shaft 137b and a link 140b, connected with its Y-shaped element 143b (see Figs. 1 and 2), and the totalizer *c* is connected with the corresponding Y-shaped element 143c by means of a bell-crank lever 315, the link 140c and the arm 138c.

In the left-hand lateral section including totalizers *d*, *e* and *f* there is also provided one such Y-shaped element 143 with appurtenant parts for each totalizer (see Fig. 1), and in the right-hand lateral section there are corresponding Y-shaped levers 143 for each of totalizers *g* and pairs of totalizers *h*, *k* and *l*, *m*.

The control mechanisms for all totalizers are identical and are to be described with reference to that of totalizer *a*. Some of the details of the control mechanisms for the totalizers *b* and *c* are to be seen to the left of the central section in Fig. 1.

In starting position the Y-shaped lever 143a is locked threefold in the following manner (see especially Fig. 5).

Arm 145a of the lever 143a rests with an inclined surface 146a against a roller 123a rotatably mounted on an arm 122a of a disk 120a secured to the main shaft 50. Arm 144a cooperates with a double-armed locking lever 148a rockable on a stud 147a. A spring 149a tends to retain one end 143xa of said lever in locking engagement with arm 144a, whereas a link 151a connects the other end 143ya of the lever with a bell-crank lever 68a operable by the analyzing keys. Lastly the Y-shaped lever 143a is also controlled by means of an angular arm 154a rotatably mounted on the main driving shaft 50 and connected with arm 141a of the Y-shaped lever 143a by means of a spring 155a secured to arm 154a and to a pin 156a provided on arm 141a and engaging the fork-shaped end 157a of a link 158a connected to arm

154a. A spring 161a tends to maintain arm 154a in such a position that an abutting surface 160a on the arm engages the roller 123a on disk 120a. Further said arm 154a is locked by two locking members. A lever or catch 69a operable by the analyzing keys and actuated by a spring 162a engages the end of arm 154a. The arm 154a is also engaged by one arm of an angular catch 165a rockable on a stud 163a and operated by a spring 164a, the other leg of said catch extending towards the periphery of disk 120a and being adapted to be acted upon by the projection 121a when driving shaft 50 is rotated.

Printing device

The actuator wheels 45 of each section are connected with a printing device which may be of any suitable type. Although the actual design of the printing devices does not form any part of the invention, a brief description of such a device will be given for the sake of completeness, reference being made to Fig. 2 and to the printing device of the central section illustrated therein.

The printing device comprises type bars 320 of a number corresponding to the number of actuator wheels and carrying types 321 which are adapted to be pressed against a paper strip on a platen roller 322. The type bars are vertically movable in guides 323. At its lower end each type bar 320 is provided with a recess 324, and engaging said recess through its one end is a double-armed lever 325. These levers are rotatably mounted on a common shaft 326 and engage with their other fork-shaped end a pin 327 on the corresponding actuator wheel 45. On rotation of said wheels the type bars 320 corresponding to actuator wheels will, consequently, be moved upwardly through such a distance as to cause the type 321 corresponding to the setting of the actuator wheel to be brought into printing position.

Provided in front of each type bar 320 is a hammer 330. The hammers are mounted on a shaft 331 carrying an arm 332 which by means of linkage is connected with an arm 333 journaled on a stud 334. Arm 333 is adapted to be actuated by an operating arm 335 fixed to the main shaft 50.

Addition in totalizer "a"

The analyzing key or keys corresponding to a business transaction in which addition in totalizer "a" is involved, have on their operating shaft 63 an arm 64 which by means of a wire 65 is connected with a bell-crank lever 67a (see Fig. 2). When the key is depressed this lever is rocked in counter-clockwise direction causing wire 115a fixed to catch 114a to be drawn downwardly and to rock said catch about its stud 113a thereby disengaging the catch from the projecting end of spindle 102a. However, the totalizer is still retained in raised position by the prolongation 138a of the bridge 104a resting on stud 136a.

When on actuation the driving shaft 50 is turned in clockwise direction as shown in Figs. 2 and 5, roller 123a leaves the inclined surface 146a on arm 145a of the Y-shaped lever 143a. This lever is, however, still retained in locked position by locking arm 148a, until on the continued rotation of shaft 50 this arm is raised by roller 123a. Thereby lever 143a is rocked by spring 158a in 70 counter-clockwise direction about shaft 142 causing link 140a and arm 138a to be drawn downwardly. The totalizer now loses its support on stud 138a and the adding wheels 100a are by spring 108a brought into engagement with the 75

intermediary wheels 170a just at the moment when the machine shaft 50 has reached the end of its forward stroke.

During the return stroke of the driving shaft 50 the adding wheels 100a, thus, engage the intermediary wheels 170a and are turned in counter-clockwise direction, thus entering the amount which during the forward stroke of the machine shaft has been introduced into the actuator wheels 45 in the manner above described.

Immediately at the end of the return stroke of the machine roller 123a strikes the inclined surface 146a on arm 145a causing Y-shaped lever 143a to be rocked in clockwise direction and link 140a to be pressed upwards, whereby the stud 136a raises the totalizer out of engagement with the intermediary wheels 170a. At the end of the return stroke when the keys are returned into starting position in the manner above described, spring 116a returns catch 114a into engagement with the projecting end of spindle 102a.

Ten transfer is effected in the following manner (see especially Fig. 11). As already described the stopping plates 25 operable by the keys are so arranged in relation to the actuator slides 28 determining the setting of the actuator wheels 45 during the forward stroke of the machine, that the actuator wheels 45 are always rotated through one tooth even when the corresponding stopping plates 25 have not been actuated, that is to say the actuator wheels corresponding to non-actuated keys are turned one tooth and actuator wheels corresponding to actuated keys are turned one additional tooth beyond the angle corresponding to the position of the depressed pin 22. The rotation of the actuator wheels one tooth is transferred to the intermediary wheels 170, however only to the half 171 of said wheels 170 in mesh with the actuator wheel but not to the other half 172 thereof (see Fig. 11). This motion of wheel half 171 is permitted as said half is capable of being turned one tooth independent of the wheel half 172 on account of the pin and slot connection 173, 174 and of the tendency of the spring 175 of maintaining pin 174 in engagement with the upper end of slot 173. Consequently, the correct setting of the actuator wheels 45 determined by the depression of the keys is transferred to the wheel halves 172 but not the additional tooth.

When during the return stroke of the machine the amount set up is transferred to the totalizer and a ten transfer is to take place, that is to say when a totalizer wheel passes in counter-clockwise direction from nine to zero, the transfer tooth 183 on such a wheel presses down the end of the ten transfer pawl 180 corresponding to said totalizer wheel. This causes the end 185 of the other arm 184 of said pawl 180 to release the pin 174 of the intermediary wheel 170 of the next higher order. During this rotation of ten transfer pawl 180 the pin 186 which was in engagement with the recess 187 in the lever 190 is moved into the recess 188 and simultaneously spring 192 rocks the lever 190 in counter-clockwise direction causing said lever to be brought into engagement with bell-crank lever 196 and the pawl 180 to be locked in this position.

When at the end of the return stroke of the machine the actuator wheels are moved through the additional tooth, there is not a corresponding motion of those intermediary wheels in which no tens transfer is to take place, since pins 174 for these wheels are locked by the ten transfer

pawl 180 of the next lower order. The final movement of the actuator wheels therefore turns the wheel half 171 by one tooth against the force of the spring 175, but wheel half 172 remains stationary. In such intermediary wheels in which a ten transfer is to take place and, consequently, pin 174 is released from its engagement with pawl 180 of the next lower order, wheel half 172 partakes in the rotation of wheel half 171 through one tooth said rotation being transferred to the respective totalizer wheel whereby ten transfer is effected. Consequently, at the end of the return stroke of the machine, the wheel halves 171, 172 of such intermediary wheels 170 in which ten transfer has taken place are not in starting position. The setting of the intermediate wheels in their starting positions is effected at the beginning of the next machine stroke in the following manner (see especially Fig. 6).

Immediately at the beginning of the rotation of the driving shaft 50 during the next machine stroke projection 122 by the influence of lever 202 rocks lever 200 about shaft 142 in clockwise direction, said motion being by link 205, bell-crank lever 206 and link 207 transmitted to bell-crank lever 197 (197a). This lever is rotated in clockwise direction and also levers 196 secured to the same shaft 195 as lever 197 (see Fig. 11). In such intermediary wheels in which ten transfer has taken place and, consequently, pin 174 lies at the upper end of the slot 173 one arm of lever 196 presses pin 174 downwardly onto the lower end of slot 173 while simultaneously tensioning the appurtenant spring 175. At the same time the other arm of lever 196 rocks lever 190 in clockwise direction while tensioning spring 192 causing the ten transfer pawl 180 to be returned into starting position in which pin 186 engages recess 187 of lever 190. Immediately as the projection 122 has moved past the lever 202 spring 127 returns lever 200 into engagement with stop 199 thereby causing the bell-crank levers 196 to be returned into starting position. Now the intermediary wheels 170 are ready for the next setting of the actuator wheels.

Subtraction in totalizer "a"

The analyzing key or keys which correspond to a business transaction in which subtraction in the totalizer *a* is involved, have on their operating shafts 63 an arm 64 connected by a wire 65 with a bell-crank lever 66a. When the key is depressed, said lever 66a is turned in counter-clockwise direction, causing the link 112a to be drawn downwardly. Thereby catch 110a is removed from lever 105a. However, this lever is still in locked position by the stud 133a of arm 134a abutting against same.

When on starting the machine the driving shaft 50 is turned in clockwise direction, disk 120 secured on said shaft is turned in the same direction causing projection 121 to release roller 124 on lever 125 (see Fig. 6). Thereby this lever loses its support and swings in clockwise direction under the influence of spring 127 drawing link 130 downwardly so that stop pin 133a on arm 134a is brought out of engagement with lever 105a. Having been released from catch 110a by the depression of the key this lever 105a swings in counter-clockwise direction under the influence of spring 107a causing the totalizer to be displaced in the same direction (towards the left in Figs. 2 and 11) so that the subtracting wheels 101a will be situated in proper position in relation to the intermediary wheels 170a. In

virtue of this displacement the end of spindle 102a is removed from pawl 114a but the totalizer is still retained in its raised position because the end 135a of the bridge 104a is still resting on stud 136a. At the same time roller 123a releases stud 145a of the Y-shaped lever 143a, said lever being, however, retained in locked position, until roller 123a raises locking arm 148a. In the manner above described the totalizer thereby loses

5 its support on stud 136a and the subtracting wheels 101a will by spring 108a be brought into engagement with the intermediary wheels 170a just at the moment when the driving shaft 50 has attained the end of its forward stroke.

10 15 During the return stroke of the driving shaft 50 the subtracting wheels 101a, thus, engage the intermediary wheels 170a which by the actuator wheels 45 are turned in clockwise direction so that the subtracting wheels are rotated in counter-clockwise direction and deduct the amount which during the forward stroke of the driving shaft was introduced into the intermediary wheels 170a. Ten transfer is effected in the manner above described.

20 25 The machine is returned into starting position by the totalizer being raised out of engagement with the intermediary wheels in the manner described above. At the moment, when the totalizer is raised, the projection 121 on disk 120 strikes roller 124 on arm 125 which is rocked in counter-clockwise direction (see Fig. 6). By link 130, bell-crank lever 131 and link 132 this movement is transferred to arm 134a the stud 133a of which returns lever 105a into starting position causing the totalizer to be returned into starting position. When in the manner above described the keys are released, spring 111a returns catch 110a into the position in which it locks lever 105a.

Subtotaling of positive amounts in totalizer "a"

30 35 40 45 The analyzing key or keys corresponding to a business transaction in which a positive amount in totalizer *a* is to be entered in some other totalizer or printed by the printing device or both, have on their operating shafts 63 two arms 64 which by means of wires 65 are connected the one with a bell-crank lever 67a and the other with a bell-crank lever 68a. When the key is depressed bell-crank lever 67a releases catch 114a in the manner above described. Rocking of bell-crank lever 68a causes locking rod 148a to release Y-shaped lever 143a. However, this lever is retained in locked position by the engagement of the roller 123a with the inclined surface 146a on same.

50 55 60 65 When the driving shaft 50 is actuated and turned in clockwise direction and, consequently, roller 123a releases lever 143a, spring 155a rocks lever 143a in counter-clockwise direction causing the totalizer to lose its support against stud 136a and the adding wheels 100a to be brought into engagement with the intermediary wheels 170a in the manner above described, this taking place immediately after the driving shaft has been started.

70 75 Consequently, during the forward stroke of the driving shaft the adding wheels 100a engage the intermediary wheels 170a setting up in the latter the amount contained in the totalizer which in this case is positive. At the end of this movement the adding wheels 100a are in zero position with the transfer teeth 183 in engagement with the trip noses 182 on the ten transfer pawls 180. The setting of the totalizer wheels 100a has also by means of the actuator wheels

45 been transferred to the type bars 320, and at the end of the forward stroke the operating arm 335 strikes arm 333 causing the hammers 330 to be turned in counter-clockwise direction striking the types 321 which are in printing position.

50 During the return stroke of the driving shaft 50 the adding wheels 100a are still in engagement with the intermediary wheels 170a, so that to the adding wheels the same amount is again transferred which said wheels had transferred to the intermediary wheels during the forward stroke of the machine.

55 The machine is returned into starting position in a manner similar to that above described, spring 149a returning locking arm 148a into starting position.

Totaling positive amounts in totalizer "a"

60 The analyzing key or keys corresponding to a business transaction in which a positive amount in totalizer a is to be transferred to the printing device or to be totaled in any other manner, have on their operating shafts 63 three arms 64 connected by means of wires 65 the first one with a bell-crank lever 67a, the second one with a bell-crank lever 68a, and the third one with a catch 69a. In the manner above described rocking of bell-crank levers 67a and 68a causes release of catch 114a and locking arm 148a. When rocked in counter-clockwise direction catch 69a releases locking arm 154a which, however, is still retained in locked position on the one hand by roller 123a and on the other hand by catch 165a.

65 Immediately after the driving shaft 50 has been started the adding wheels 100a are brought into engagement with the intermediary wheels 170a as above described. When at the same time the Y-shaped lever 143a is rocked in counter-clockwise direction the stud 156a on arm 141a of said lever has attained the bottom of the recess 157a in the link 158a by the influence of spring 155a.

70 During the continued forward stroke of the driving shaft the totalizer is actuated in the same manner as described above with reference to the subtotaling of a positive amount. At the end of the forward stroke, just when the adding wheels 100a are in zero position and printing has taken place projection 121a strikes the upper leg of V-shaped catch 165a turning said catch in counter-clockwise direction thereby releasing locking arm 154a which has already been released by roller 123a. Spring 161a rocks locking arm 154a in clockwise direction rocking by link 158a and pin 156a the Y-shaped lever 143a in the same direction. This causes the totalizer to be raised out of engagement with the intermediary wheels 170a by the influence of link 140a and arm 138a.

75 During the return stroke of the driving shaft roller 123a strikes the inclined surface 146a on Y-shaped lever 143a and also the surface 160a on locking arm 154a causing said lever and arm to be returned into starting position under the influence of their springs 155a and 161a. Simultaneously pawl 165a and catch 69a are returned into engagement with the locking arm 154a under the influence of their springs 164a and 162a.

Mechanisms for directing totalizer "a" to totalize negative amounts

80 Provided on each side of totalizer a (see especially Figs. 10 and 11) is an arm 210 mounted on stud 109a (109 Fig. 10), said arms being connected with each other by a rod 211 slidable in a slot 212 in the machine frame plate during the

displacement of the totalizer. Provided for each denomination of the totalizer are two arms 213, 214. Arm 213 rests with its fork-shaped end 215 on rod 211 and is provided with two teeth 216 engaging the adding wheels 100 in the raised position of the totalizer and with a projection 218 for the return of the arm. Arm 214 is rockable on a shaft 217 secured between arms 210. A spring 218 connects arms 213 and 214 with each other.

85 By means of an angularly bent projection 220 each arm 213 rests on a projection 221 of arm 214 of the next lower order (Fig. 14). The arm 213 which corresponds to the unit denomination rests with its supporting plate 220 on the frame as shown at 226 in Fig. 10. Each arm 214 rests on an angularly bent portion 227 of arm 214 of the next lower order (see especially Fig. 14) except that no bent portion 227 is supplied on arm 214 of the next to the highest order.

90 Fixed to each subtracting wheel 101 is an additional disk 222, and each of said disks except that of the highest order which is designed in a manner to be described later on has a recess 223, see Fig. 14. Extending downwardly from each arm 214 is a tongue 224 sliding on the periphery of the corresponding disk 222 and pressed into engagement therewith by the spring 218. Consequently, each arm 214 can take up either of two positions, viz. a lower position when tongue 224 engages the recess 223 of the corresponding disk 222, this being the case when the corresponding wheel 101 occupies the "nine" or starting position, and a raised position, when said tongue rides on the non-recessed portion of the periphery of the disk. Arm 213 corresponding to the unit denomination occupies always lowered position. A rod 225 fixed between the arms 210 serves as stop for arms 214.

95 Arm 213 which, as stated above, rests with its supporting plate 220 on the projection 221 of arm 214 of the next lower order will, consequently, also occupy either of two positions depending on the position of the arm 214 of the next lower order. Arm 213 is provided with a shoulder 230. Arms 233 are rockable on studs 232x on the stationary machine frame, and secured to said arms 233 is a locking rod 231 adapted in its raised position to engage the shoulder 230 of such arms 213 which are in their lower position (see Fig. 12). A spring 234 serves to maintain the locking rod 231 in starting position (see Fig. 11). To one of the studs 232x is attached an arm 232 (see also Fig. 10), and said arm 232 is connected by means of a wire 235 (235a, Fig. 2) with a bell-crank lever 70a operable by the analyzing keys. In Fig. 11 the locking rod 231 and the arms 213 and 214 are shown in the position which they assume at the beginning of the forward stroke of the main shaft, whereas in Fig. 12 the locking rod 231 and one arm 214 are shown in raised position in full lines and another arm 214 in lowered position in dotted lines.

100 Journalled on a stud 240a (see especially Fig. 5) is a double-armed lever 241a connected at its one end by a wire 242a with the bell-crank lever 71a operable by the analyzing keys and controlled by a spring 248a. At its other end lever 241a is provided with a pin 243a adapted to cooperate with the disk 120a secured on the main driving shaft 50. By means of a spring 244a lever 241a is connected to an arm 246a rockable about a stud 245a and controlled by a spring 247a, said arm being by a link 250a connected with a bell-crank lever 251a which in turn by a link 252a (252) is connected to an arm 253 (see Figs. 2

and 11). This arm 253 is controlled by a spring 254 and secured on a shaft 255 which carries an arm 256. A rod 257 connects the upper end of said arm with that of a similar arm on the opposite side of the totalizer.

Subtotaling negative amounts in totalizer "a"

The analyzing key or keys corresponding to a business transaction in which the above totaling forms an essential part have on their operating shafts 63 three arms 64 connected by wires 65 with a bell-crank lever 66a, 68a and 70a. When the key is depressed and said levers are rocked in counter-clockwise direction, 66a releases catch 110a, 68a releases locking rod 148a and 70a causes by drawing wire 235 (235a) downwardly arm 233 to be rocked in clockwise direction, thereby raising locking rod 231.

When then the driving shaft 50 is rotated in clockwise direction during the forward stroke of the machine, lever 105a is swung on its stud 106a in counterclockwise direction bringing with it the totalizer so as to place the subtracting wheels 101 in readiness for engagement with the intermediary wheel's 170. In the totalizer wheel of the unit denomination arm 213 occupies its lower position. In those totalizer wheels 101 which occupy starting position, i. e. they stand at "9", and in which, consequently, tongue 228 engages recess 223 the corresponding arm 213 also occupies its lower position provided that the arm 214 of the next lower order also occupies this position. If this is not the case, arm 213 is retained in raised position by the bend 227 of arm 214 of the next lower order (see Figs. 10, 11 and 12). The arms 213 of other totalizer wheels are in raised position. When the totalizer is displaced in the manner above described locking rod 231 will, consequently, strike the shoulder 230 on all arms 213 which are not raised, said arms being thereby stopped in their movement, whereas the raised arms 213 take part in the continued displacement. This results in the corresponding adding wheels 100 being turned by the teeth 216 in clockwise direction through an angle corresponding to one tooth causing the corresponding subtracting wheels 101 to be turned one tooth in counterclockwise direction. In this manner the subtracting wheel of the unit denomination and the adjacent wheels standing on nine will be automatically supplied with a unit which is necessary for a correct indication or printing.

Immediately when the totalizer has been displaced in this manner roller 123a leaves the inclined surface 146a on the Y-shaped lever 143a causing the subtracting wheels 101 to be brought into engagement with the intermediary wheels 170 as described above, this taking place immediately after the driving shaft is started. At the same time the adding wheels 100 leave their engagement with the teeth 216.

During the forward stroke of the driving shaft the subtracting wheels 101 are in engagement with the intermediary wheels 170 setting said wheels on the negative amount contained in the totalizer, which amount is not the complement to that of the adding side of the totalizer but the real negative amount contained in the totalizer due to the addition of the fugitive one. At the end of this movement the subtracting wheels are in zero position, and the negative amount is printed.

In order more clearly to illustrate the function the following example is given:

Assume the totalizer is clear; the positive

wheels 100 will then stand at .. 0000, while the negative wheels 101 will stand at .. 9999, and the transfer tooth 183 on the adding wheels 100 is just to the right of trip nose 182, as shown in Fig. 5 11, while the transfer tooth on the subtracting wheels 101 would be to the left of said trip, if the bridge 104 with the two wheels 101 and 100 were moved to the left (see Figure 12).

Now assume that 180 is added.

10 The adding wheels 100 will then read ... 180
The subtracting wheels 101 will then read ... 9819

Assume further that 290 is subtracted.

15 The adding wheels 100 will read ... 9890
The subtracting wheels 101 will read ... 109

If a total is now taken the fugitive one mechanism will set the adding wheels 100a to read ... 9889 and the subtracting wheels 101 to read ... 110

20 The subtracting wheels 101 showing the true negative total will mesh with the actuator wheels 170 on the forward stroke and will condition the print bars to print the total accordingly.

During the return stroke of the driving shaft 25 the subtracting wheels 101 are still in engagement with the intermediary wheels 170 and are now set on the same amount which they delivered to the intermediary wheels during the forward stroke.

30 When the totalizer is raised at the end of the return stroke the adding wheels 100 are again brought into engagement with the teeth 216. When then the totalizer is returned by the influence of lever 105a only those arms 213 are

35 first moved which are not locked by the locking rod 231, whereas the arms 213 which are locked by said rod are not actuated, until rod 211 strikes the bottom of slot 215. Meanwhile the adding wheels 100 corresponding to the locked arms 213 which during the displacement of the totalizer were turned one tooth have been turned one tooth in opposite direction thereby returning the totalizer into starting position.

When the keys are released spring 234 returns 45 locking rod 231 into starting position.

Totaling negative amounts in totalizer "a"

The analyzing key or keys corresponding to a business transaction in which the above totaling from totalizer "a" is involved have on their operating shafts 63 five arms 64 each connected by a wire 65 with one lever 66a, 68a, 69a, 70a and 71a. Such a key connection is shown diagrammatically in Fig. 7. When the key is depressed said levers are rocked as above described

50 so that 66a releases catch 110a, 68a releases catch 148a, 69a releases locking arm 154a and 70a raises locking rod 231. Rocking of bell-crank lever 71a causes the lever 241a to be rocked in counter-clockwise direction so that stud 243a is brought into engagement with disk 120a.

Immediately when the driving shaft has been started the subtracting wheels 101 are brought into engagement with the intermediary wheels 170 after having been automatically supplied with a fugitive one as described above. During the continued forward movement of the driving shaft the subtracting wheels 101 are, consequently, in engagement with the intermediary wheels 170, and at the end of the forward stroke they are in zero position and the negative amount contained in the totalizer is printed.

Meanwhile following movements have taken place. When the driving shaft has completed 70 about half its forward stroke, projection 121a

on disk 120a strikes pin 243a on lever 241a (see Fig. 5) causing arm 246a to be rocked in counter-clockwise direction, said movement being by link 250a, bell-crank lever 251a and link 252a transferred to shaft 255 and arm 256. The latter is turned in clockwise direction causing rod 257 to strike projection 219 (see Figs. 11 and 12) on those arms 213 which are in raised position and, consequently, have not been locked by locking rod 231 during the displacement of the totalizer, said arms 213 being displaced in such direction that their supporting plate 220 loses its support on the projection 221 on the arm 214 of the next lower order. This results in said arms 213 being moved downwardly under the action of the springs 218, until they rest on the locking rod 231 with the underside of their shoulder 230. The arms slide on the locking rod 231, until the shoulder leaves same, whereupon they fall down to rest with their underside on the locking rod 231 and are locked by said rod.

When during the continued forward movement of the driving shaft projection 121a releases stud 243a on the lever 241a, spring 247a returns arm 246a into starting position, rod 257 being simultaneously returned into starting position. At the end of the forward stroke just when the subtracting wheels 101 are in zero position and indication or printing has taken place, projection 121a strikes the upper leg of the angular catch 165a resulting in the subtracting wheels 101a in their zeroized position being brought out of engagement with the intermediary wheels 170 simultaneously as the adding wheels 100 are brought into engagement with the teeth 216.

Then the return movement of the driving shaft sets in. Roller 123a is returned into engagement with the surface 160a on arm 154a and returns said arm while tensioning springs 155a and 161a, the arm being simultaneously locked by catch 165a. Meanwhile projection 121a has also struck roller 124a resulting in lever 105a being returned into starting position bringing with it the totalizer. As all of the arms 213 are now locked by locking rod 231, these arms do not take part in the return movement, until rod 211 strikes the bottom of slot 215. When this occurs all of the adding wheels 100 have been turned one tooth in counter-clockwise direction by the teeth 216 and, consequently, all subtracting wheels one tooth in clockwise direction. Thereby the totalizer is restored into starting position.

When the keys have been released spring 248a returns bell-crank lever 71a into starting position.

When taking a total or a subtotal the actuator slides 28 must, evidently, be able to perform a movement corresponding to nine teeth. In the embodiment above described it is assumed that for this reason all of the "9" digit keys D are depressed. However, to avoid this manipulation means may be provided by which the actuator slides 28 are automatically released from their engagement by the stopping plates 25 when a total or subtotal key is depressed. Two embodiments of such a means are shown in Figs. 16, 17, 18 and 19, 20, 21, respectively.

According to Figs. 16 to 18, inclusive, the stopping plates corresponding to the two first and two last rows of registering, totaling and zeroizing keys are, as distinguished from those corre-

sponding to the key rows C and D, divided into two parts 25x and 25y, the pins 23 of the keys

A to A
1 to 9

5 inclusive, co-operating with the stopping plates 25x, whereas the pins 22x and 22y (see below) of the keys

B to B
1 to 4

10 inclusive, and

R
IV

15 to

R
VII

inclusive, co-operate with the stopping plate 25y. Secured to each stopping plate 25x is a

20 bent arm 25z which extends behind the corresponding stopping plate 25y.

Extending transversely of the key board is a rod 29 having studs 29x engaging to the right of the stopping plates 25y and studs 29y engaging to the left of the stopping plates 25 of the digit key rows D. A spring 29z tends to maintain the rod 29 with its studs 29x engaging the respective stopping plates.

Depression of any of the registering keys A 30 has no influence upon the stopping plates of the other key rows, but when a key B or a key R is depressed, the corresponding stopping plate 25y is turned about its shaft 26 causing the rod 29 to be moved to the right in Figs. 17 and 18 35 whereby the studs 29y turn the stopping plates 25 of the digit key rows D so that the actuator slides 28 can pass freely.

Another embodiment of this means for releasing the actuator slides 28 when taking a total 40 is shown in Figs. 19 to 21, inclusive. Here the stopping plates 25 of the digit key rows D are provided with a projection 340 engaging recesses 341 in a rod 342 extending transversely of the key board (see Fig. 21), said recesses having such a size as to permit the stopping plates to be turned on depression of the keys when the rod 342 assumes its normal position. A spring 343 tends to maintain rod 342 in said position. A bell-crank lever 344 fulcrumed at 345 bears on the end of rod 342 and is connected by a link 346 with the one arm of a bell-crank lever 347 fulcrumed at 348 (see Fig. 19). The other arm of said lever 347 co-operates with a roller 123x on a disk 120x secured to shaft 50 and is locked by 55 a catch 349 which by means of a wire 65 is connected with an arm 64 of the operating shaft 63 of each of the keys B and R. A spring 350 tends to maintain the bell-crank lever 347 in engagement with the roller 123x.

On depression of any key B or R the catch 349 is actuated to release bell-crank lever 347. On rotation of the driving shaft 50 the lever 347 is rotated in clockwise direction under the action of the spring 350 and, through link 346, moves 60 the releasing rod 342 to the right in Fig. 20, causing the stopping plates 25 of the digit key rows D to be turned out of the path of the corresponding actuator rods 28 which are now free to move to the left.

70 *Means for locking a registering key when a totalizer is not in zeroized position*

This means which is shown in Fig. 2 as applied to totalizer b comprises a plurality of arms 261b (see especially Fig. 15) secured on a shaft 260b

extending along the totalizer, one arm for each of pairs of totalizer wheels 100b and 101b. At their free ends the arms 261b are each provided with a nose 262b adapted to slide on the periphery of a disk fixed to each of the totalizer wheels, e. g. the disk 222b of the subtracting wheels 101b. Secured to shaft 260b is an arm 264b which is actuated by a spring 274b tending to retain the arms 261b in sliding engagement with the disk 222b. The disks 222b are each provided with a recess, e. g. the same recess 223b serving for the supply of the fugitive one as described above, the nose 262b being adapted to engage said recess, when the corresponding totalizer wheel is in starting position. By means of a link 265b (see Fig. 2), a bell-crank lever 266b, a link 267b, a bell-crank lever 268 and a link 270 the arm 264b is connected with one arm of a bell-crank lever 271 to which the key spring 20 of key

A

6

is secured tending to bring the other arm of the lever 271 into engagement with a recess in the key rod 21 of said key.

When all of the arms 261b engage the recess 223b in the disks 222b, that is to say when all totalizer wheels are in starting position, bell-crank lever 271 is out of engagement with the key rod 21 and, consequently, the corresponding key can be depressed freely. When on the contrary, due to wrong setting one or more of the totalizer wheels 101b do not occupy starting position and, consequently, the corresponding arms 261b are in raised position (as shown in Figs. 2 and 14) bell-crank lever 271 engages the key rod 21 thus preventing the key from being depressed. In Fig. 2 it is shown how two registering keys

A and A
6 and 7

are controlled in this manner.

Means for setting a totaling key to total positive or negative amounts contained in a totalizer

This means is shown in Fig. 2 as applied to totalizer a, but, evidently, the other adding and subtracting or balancing totalizers may also be provided with such means.

As seen in detail in Figs. 10 and 13, disk 222x of the highest denomination has no recess 223 but instead thereof a spring finger 280. Further arm 214x of said order terminates in a bend 281 and has its tongue 224x somewhat displaced as compared with the tongues 224 of the lower denominations. As long as the totalizer contains a positive amount tongue 224x rests on a catch 282 rockably mounted on a stud 283 fixed to a supporting plate 284 secured to one arm of bridge 104. Rockably mounted on a stud 285 on said plate 284 is an arm 286 having two recesses 287 and 288 adapted to be engaged by catch 282. A spring 290 wound about stud 285 and engaging a stop 291 on plate 284 and another stop 292 on arm 286 serves to retain catch 282 in engagement with either of the recesses 287 and 288.

Pivoted on a stud 295 on the frame (see also Figs. 2 and 11) is an angularly bent lever 296 one arm of which terminates so as to be operable by the end 281 of arm 214x, whereas the other arm is connected by a link 297, bell-crank lever 298, link 299, bell-crank lever 300 and link 301

with a bell-crank lever 302 adapted to control the totaling key

B

3

5 in the following manner, said key being shown set for positive totals in Fig. 2 in depressed and in Fig. 4 in starting position.

This key has two key rods 21x and 21y each actuated by a spring 20x and 20y, respectively, and having at its upper end a recess 305x and 305y, respectively. The key stem is movably connected to a rod 306 carrying a pin 308 capable of being brought into engagement with either of the recesses 305x or 305y. A spring 307 tends to engage pin 308 with recess 305x. A link 309 connects rod 306 with bell-crank lever 302. The operating shaft 63 of the key rod 21x carries an arm 64 connected to an adding bell-crank lever 67a and shaft 63 of key rod 21y has an arm 64 connected to a subtracting bell-crank lever 66a.

When the totalizer wheel 100 of the highest denomination passes from zero to nine, that is to say when an amount is subtracted which is greater than that actually contained in the totalizer, and the totalizer thus contains a negative amount, the shoulder 280 of disk 222 strikes the catch 282 rocking same in counter-clockwise direction as seen in Fig. 10. Thereby catch 282 is shifted from engagement with recess 287 into engagement with recess 288 and tongue 224x loses its support on the catch. When during the preceding forward stroke the totalizer was displaced towards the left in Figs. 2 and 11, the end 281 of arm 214x moved past the lever 296, and at the end of said stroke, when the subtracting wheels are in engagement with the intermediary wheels, arm 214x has moved downwardly into engagement with rod 225 lying now on the left-hand side of lever 296. When during the return stroke the totalizer is returned into starting position, the end 281 of arm 214x strikes lever 296 rocking same in clockwise direction as shown in Figs. 2 and 11. This movement is transferred to rod 306 which is rocked out of engagement with recess 305x in the positive key rod 21x and into engagement with recess 305y in the negative key rod 21y, the key

B

3

being now set to take a negative total.

If in this position further items are subtracted from that contained in the totalizer and the totalizer wheel of the highest denomination is again moved from zero to nine, the finger 280 of disk 222 passes past the catch 282 while the same is maintained in engagement with recess 288 on account of spring 290. During the machine operation lever 306 is moved into engagement with the positive key rod 21x under the action of spring 307, but at the end of the operation lever 306 is again returned into engagement with the negative key rod 21y, as lever 296 is locked by the end 281 of arm 214x, so that key

B

3

is again in position to take a negative total. When due to addition of a sufficient amount the totalizer wheel of the highest denomination passes from nine to zero, the adding wheels of the totalizer being then in engagement with the intermediary wheels, catch 282 is returned into the position shown in Fig. 10. When during the return stroke the totalizer is returned into raised

position catch 282 raises the tongue 224x of arm 214x causing the end 281 of said arm to be out of the path of the lever 296. Thereby rod 306 is caused to remain in engagement with recess 305x under the action of spring 307. The key

13

3

is now in position to take a positive total.

In a machine having separate keys for taking positive and negative totals of a totalizer it is possible to utilize the lever 296 to lock the key for taking positive totals when the totalizer has gone over to the negative side and vice versa so as to make the operator aware of whether the amount contained in the totalizer is positive or negative. For this purpose the key rods 21x and 21y are operated by separate keys and the link 306 is fulcrumed on the machine frame locking the key rod 21x or 21y with the recess 305x or 305y of which its pin 308 is in engagement.

I have now described the function of one totalizer and the different mechanisms for setting for different senses of calculation. Before I proceed to describe a specific example of the application of the invention on a book-keeping machine, I will first describe some examples of the connections between the totalizers and the registering and totaling keys.

A given key may be adapted to select two or more totalizers and to set the selected totalizers for addition. In this case the catches 114 of these totalizers are each controlled by a bell-crank lever 67 connected by a wire to an arm 64 on the operating shaft 63 of said key.

A given key may be adapted to select two or more totalizers and to set the selected totalizers for subtraction. In this case the catches 110 of these totalizers are each controlled by a bell-crank lever 66 connected by a wire 65 to an arm 64 on the operating shaft 63 of the key.

A given key may be adapted to select two or more totalizers and to set some of them for addition and the other for subtraction, said key being connected with the adding totalizer by a bell-crank lever 67 and with the subtracting totalizer by a bell-crank lever 66.

In subtotaling a positive amount contained in a totalizer and transferring said amount additively to one or more totalizers and subtractively to one or more other totalizers or in printing such a positive amount, the combinational key is connected with the totalizer to be subtotalized by a lever 67 and a lever 68, with each of the totalizers selected for addition by a lever 67 with each of the totalizers selected for subtraction by a lever 66. In totaling said positive amount the key in question is connected with the totalizer to be totaled also by a lever 69.

In subtotaling a negative amount contained in a totalizer and transferring said amount additively to one or more totalizers and subtractively to one or more other totalizers, or in printing said negative amount, the combinational key is connected with the totalizer to be subtotalized by levers 66, 68 and 70, with each of the totalizers selected for addition by a lever 67 and with each of the totalizers selected for subtraction by a lever 66. In totaling said negative amount, the key in question is connected with the totalizer to be totaled also by a lever 69 and a lever 71.

In general, it is to be noted that the levers 67 set the totalizers for addition; the levers 66 set the totalizers for subtraction; the levers 67 and 75

68, in combination, set the totalizers for subtotalizing a positive amount; the levers 66, 68 and 70, in combination, set the totalizers for subtotalizing a negative amount; the lever 69 sets the totalizers for totaling a positive amount; and the levers 69 and 71, in combination, set the totalizers for totaling a negative amount.

I will now proceed to describe the mode of operation of the machine in a numerical example.

In the book-keeping diagram shown in Fig. 22 reference letters *a*, *b* etc. to *m*, inclusive, indicate the totalizers of the machine, but only the function of totalizers *a*, *b*, *c*, *d*, *e*, *f*, and *g* will be more fully described. Each of said totalizers has six different methods of operation: two for the registration of amounts, viz, addition (+) and subtraction (-); and four for totaling, viz. subtotalizing positive amounts

$$\left(\begin{array}{c} + \\ + \end{array} \right)$$

totalizing positive amounts

$$\left(\begin{array}{c} + \\ 0 \end{array} \right)$$

subtotalizing negative amounts

$$\left(\begin{array}{c} - \\ + \end{array} \right)$$

and totaling negative amounts

$$\left(\begin{array}{c} - \\ 0 \end{array} \right)$$

35 In Figure 22 the dots and the horizontal lines indicate which totalizers are actuated and in what sense they are actuated. For example, when the key *A* of Figure 22 is depressed, totalizers *a* and *b* are actuated in a positive direction, and totalizer *f* is actuated in a negative direction. Thus the horizontal lines indicate which of the totalizers are actuated and, of course, that they are actuated simultaneously, and the dots indicate the sense of operation of the selected totalizers.

It is assumed that said seven totalizers serve the following purposes.

Totalizer *a* registers capital balance.

Totalizer *b* serves to check the correct entering in the totalizers "a" and "c" of old balances and the mechanical operation of the totalizers.

Totalizer *c* registers interest balance.

Totalizer *d* registers the sum of capital deposited or withdrawn.

Totalizer *e* registers the sum of interest accruing from capital deposited or withdrawn.

Totalizer *f* registers the sum of the differences between incoming and outgoing capital balances (positive or negative).

Totalizer *g* registers the sum of the differences between incoming and outgoing interest balances (positive or negative).

65 Further it is assumed that one of the customers of a bank at a certain occasion has a positive capital balance (demand on the bank) of 190 crs. and an interest balance thereon until the end of the year of 4.32 crs. forming a total balance in his favour until the end of the year of 194.32 crs. On August 2, he withdraws an amount of 70 crs., the interest thereon until the end of the year amounting to 1.41 crs.

The book-keeping is then effected in the following manner:

(a) The amount of the capital balance 190 is

set up on the key board by the amount keys D and then key

A
1

is depressed. In the manner above described this key is by means of arms 64 and rods 65 connected to an adding bell-crank lever 61a controlling totalizer a, an adding bell-crank lever 67b controlling totalizer b and a subtracting bell-crank lever 66f controlling totalizer f. When the machine thereafter is started the amount 190 is, consequently registered additively in totalizers a and b and subtractively in totalizer f and further the amount is printed.

(b) The amount of the interest balance, 4.32 15 crs., is set up by the amount keys D and the key

A
3

is depressed. This key selects totalizers b, c and g setting the two first-mentioned for addition and the last-mentioned for subtraction. At the operation of the machine the amount is thus registered in the totalizers in the corresponding manner and further the amount is printed.

(c) The sum of capital and interest, 194.32 crs., is set up by the amount keys D and the key

A
5

is depressed, said key selecting totalizer b for subtraction. Consequently, at the operation of the machine this amount is subtracted in said totalizer and printed.

When now the above-said amounts have been correctly read off and set up by the amount keys, the totalizer b will attain zero position, as said totalizer has added the two first amounts and subtracted the third one which is the sum of the former. When on the contrary, any of the three amounts has been incorrectly read off or set up by the amount keys, totalizer b has not been zeroized by the Operation c, resulting in the keys

A and A
6 and 7

having been locked by the catch 271 as described above and are, thus, prevented from being depressed. In such case the operator can not proceed with the following Operation d without becoming cognizant of the fact that some of the old balances have been incorrectly set up.

Presuming that the three above operations have taken place correctly, the following operations follow:

(d) The amount withdrawn, 70 crs., is set up by the amount keys D and the key

A
7

is depressed. This key selects totalizers a and d setting the former for subtraction and the latter for addition. When the machine is started the amount is registered in corresponding manner and is printed.

(e) The interest accruing from the amount withdrawn, 1.41 crs., is set up by the amount keys D and the key

A
9

is depressed selecting the totalizers c and e and setting the former for subtraction and the latter for addition. At the operation of the machine 78

the amount is registered correspondingly and printed.

Now all amount registering operations have been performed and it remains to let the totalizers of the machine read off their amounts to the printing devices and to other totalizers for controlling purposes, this being effected in the following manner.

(f) The key

10

B
1

is depressed selecting totalizers a, b and f and determining the sense of calculation of said totalizers in such a manner that totalizer a is set for subtotaling from the positive side, totalizer b for subtraction and totalizer f for addition, all under the presumption that the amount contained in totalizer a is positive. When the machine is 20 started totalizer a transfers to the actuator wheels its amount, 120 crs., which is printed on the journal and on the account card, and is registered in totalizers b and f in the manner described. However, after operation the amount is still contained in totalizer a.

(g) Key

B
2

30 is depressed selecting totalizers a, b, c and g and determining the sense of calculation of said totalizers in such manner that totalizer c is set for totaling from the positive side, totalizers a and g for addition and totalizer b for subtraction, 35 all under the presumption that the amount contained in totalizer c is positive. When the machine is operated, totalizer c transfers its amount, 2.91 crs., to the other totalizers in the manner above set forth and is zeroized. Simultaneously 40 the amount is printed.

(h) Key

B
3

45 is depressed selecting totalizers a and b and determining the sense of calculation of said totalizers in such a manner that totalizer a for totaling from the positive side and totalizer b is set for addition, all under the above presumption that the amount in totalizer a is positive. On operation of the machine totalizer a transfers its amount, 122.91 crs., to totalizer b and is zeroized. Simultaneously the amount is printed.

(i) Finally key

B
4

is depressed selecting totalizer b and setting same for totaling from the positive side. If 60 the totalizers have calculated correctly this amount must be zero and is printed on operation of the machine.

Above it is assumed that the capital and interest balances are positive amounts. I will now describe the function of the machine, when said amounts are negative. For this purpose it is assumed that the customer in question on Sept. 9 withdraws an amount of 350 crs. the interest thereon to the end of the year being 7 crs. Hereby, the customer will owe the bank an amount instead of having a demand on same. The book-keeping is then effected as follows:

(a) to (c) The old capital balance, 120 crs., the old interest balance, 2.91 crs., and the old balance to the favour of the customer 122.91 crs., are

in turn set up on the amount board and registered as before while using the keys

A, A and A
1 3 and 5

(d) and (e) The amount withdrawn, 350 crs., and the interest accruing therefrom, 7 crs., are also registered as before while using the keys

A and A
7 and 9

As thereby the respective amounts are subtracted in totalizers *a* and *c*, said totalizers proceed to negative amounts. The keys

B . . . B
1 4

inclusive, will thereby during the following machine operation be shifted to the negative side, keys

B, B and B
1 2 and 4

being also provided with such shifting means as described above with reference to key

B
3

(f) When key

B
1

is depressed totalizers *a*, *b* and *f* are selected as before but now the sense of calculation of the totalizers is determined in such a manner that totalizer *a* is set for subtotaling from the negative side, and both of the totalizers *b* and *f* are set for subtraction. On operation of the machine totalizer *a* transfers its amount, 230 crs., (the automatic unit supplying means having been set in function as above described) to totalizers *b* and *f* in a corresponding manner and simultaneously the amount is printed. After operation the amount is still contained in totalizer *a*.

(g) On depression, key

B
2

selects as before totalizers *a*, *b*, *c* and *g* determining, however, in this case the sense of calculation of said totalizers in such a manner that totalizer *c* is set for totalizing from the negative side and totalizers *a*, *b* and *g* are set for subtraction. On operation of the machine totalizer *c* transfers its amount, 4.09 crs., to the other selected totalizers in corresponding manner and is zeroized. The amount is printed.

(h) On depression key

B
3

selects totalizers *a* and *b* and determines the sense of calculation thereof in such a manner that totalizer *a* is set for totaling from the negative side and totalizer *b* is set for addition. On the operation of the machine totalizer *a* transfers its amount, 234.09 crs., to totalizer *b* and is zeroized and simultaneously the amount is printed to show the character of the balance.

(i) When finally the key

B
4

is depressed totalizer *b* is set for totaling from the negative side. If totalizers *a*, *b* and *c* have calculated correctly, the negative side of totalizer *b* must in this case record zero which is printed on the journal and on the account card.

Now the old balances are of negative character and, consequently, the registration of the amounts the next time will be different. If on Dec. 1 the customer in question deposits 200 crs. from which an interest to the end of the year of 2.20 crs. accrues, the book-keeping of this transaction is effected as before with the difference that the keys

10 A and A
2 and 4

are used instead of keys

A and A
1 and 3

15 to register the old balances and keys

A and A
6 and 8

instead of keys

20 A and A
7 and 9

for registering the amounts of deposited capital and interest as the amount 200 crs. is deposited and not withdrawn.

25 From the above description of the specific example and from the diagram shown in Fig. 22 it is clear that in close agreement to Fig. 2 keys

A and A
6 and 7

30 are each provided with means to effect their locking in raised position, when a totalizer, in the example referred to totalizer *b*, is not in zeroized position.

35 Further the totaling keys

B to B
1 to 4

40 inclusive, are each provided with key rod shifting means automatically to set them to total positive or negative amounts according as one or more totalizers contain a positive or negative amount, that is to say these keys are each provided with double key rods *21x* and *21y* as well as link connections to the corresponding totalizer or totalizers as described above with reference to totalizer *a*.

45 In the embodiment shown totalizers *a*, *b* and *c* are, as seen, horizontally calculating totalizers, whereas totalizers *d*, *e*, *f* and *g*, are vertically balancing totalizers. After a number of entries referring to a certain period of book-keeping are registered in the machine, the amounts contained in totalizers *d*, *e*, *f* and *g* may be obtained by 55 means of the keys

R to R
IV to VII

60 inclusive, which serve simultaneously as zeroizing keys for the corresponding totalizer. It should be observed, that these zeroizing keys are also equipped with key rod shifting means.

65 Instead of using a separate analyzing key for each combination of factors to be recorded, one may use one analyzing key for two or more of said combinations, or even one single analyzing key for all combinations desired. A key for two or more combinations of factors should be adapted to be set in different positions each position corresponding to such a combination as is more clearly described and shown in a co-pending continuation-in-part application filed by Ernst Vilhelm Nyberg on November 30, 1937, Serial No. 177,377.

70 75 In the embodiment described and illustrated

herein the operating means consists of keys mechanically connected to the controlling means of the totalizers. Said operating means may also consist of electromagnets electrically connected to said controlling means as is also shown and described in said copending application.

What I claim is:

1. In accounting apparatus having a plurality of actuators, an adding and subtracting totalizer, mechanism movably supporting said totalizer for engagement with the actuators in different relations thereto for positive total taking, and for negative total taking, means to control the totalizer for a selected type of engagement, and means to select the type of engagement, and means controlled by the selecting means operating to enter a fugitive one in said totalizer when the amount contained therein is negative.

2. In accounting apparatus having a plurality of actuators, an adding and subtracting totalizer, mechanism for movably supporting said totalizer for engagement with the actuators in different relations thereto for addition and positive total taking and for subtraction and negative total taking, a key for setting said mechanism to condition the totalizer for either type of engagement, toothed aligning means for maintaining said totalizer in position when out of engagement with said actuators, and movable with the totalizer, and means controlled by said key to retain said aligning means associated with the lowest denominational order of the totalizer in position while said totalizer is being moved to condition it for subtractive total taking whereby a fugitive one is inserted in the totalizer prior to the total taking operation.

3. A true negative totalizer comprising a set of adding wheels, a set of subtracting wheels in mesh with corresponding denominational ones of said adding wheels, actuating means, means for maintaining said totalizer wheels in alignment when not in engagement with said actuating means, said means comprising rack sections in engagement with said adding wheels, means to position said subtracting wheels in position for subsequent engagement with said actuating means for negative total taking, said rack sections normally moving with said wheels, and means operable in advance of the movement of said positioning means for holding the rack section of the wheel of lowest denominational order during movement of the positioning means whereby the fugitive one is inserted into the subtracting wheel of lowest order prior to the engagement of the subtracting wheels with said actuating means.

4. A true negative totalizer comprising a set of adding wheels, a set of subtracting wheels in mesh with corresponding denominational ones of said adding wheels, actuating means, means for maintaining said totalizer wheels in position when not in engagement with said actuating means, said means comprising rack sections in engagement with said adding wheels, means for moving said subtracting wheels into position for engagement with said actuating means for negative total taking, said rack sections normally moving with said wheels, and means operable in advance of said moving means for causing the position maintaining means of the wheel of lowest denominational order to move relatively to said wheel whereby the fugitive one is inserted into the subtracting wheel of lowest order prior to

the engagement of the subtracting wheels with said actuator, and means under control of the subtracting wheel of each order to control the rack section of next higher order and for causing movement of the rack section relative to its corresponding subtracting wheel when the considered order subtracting wheel is at starting position and means preventing said control of the rack section of higher order when a subtracting wheel of any lower order is at other than starting position.

5. A true negative totalizer comprising a set of adding wheels, a set of subtracting wheels in mesh with corresponding denominational ones of said adding wheels, actuating means, means for maintaining said totalizer wheels in position when not in engagement with said actuator, said means comprising rack sections in engagement with said adding wheels, and normally moved as a unit with said totalizer when said totalizer is shifted into position for engagement of said subtracting wheels with said actuators, means for shifting said totalizer to position for subsequently engaging said subtracting wheels with said actuators at the beginning of a machine cycle in which negative total taking is to occur, and means operable in advance of said shifting means for stopping said position maintaining means of the lowest order adding wheel to cause relative motion between said wheel and said position maintaining means whereby the fugitive unit is added into said lowest order subtracting wheel prior to engagement of said wheel with its actuator during the total taking cycle.

6. A totalizer comprising actuating means, a set of adding wheels, a set of subtracting wheels, said adding and subtracting wheels being adapted to be rotated by said actuating means, two total taking control means, means carried by the subtracting wheel of highest denominational order operable to effect a selection of said total taking control means, means operable by said total taking control means to initiate a total taking cycle, and means operable at the beginning of a negative total taking cycle to cause insertion of a fugitive one into the lowest denominational order subtracting wheel and of a unit into such higher orders as is necessary and during the same cycle subsequent to the completion of total taking to remove a unit from each subtracting wheel.

7. A totalizer comprising actuating means, a set of adding wheels, a set of subtracting wheels, said adding and subtracting wheels being adapted to be rotated by said actuating means, two means controlling the taking of sub-totals, means carried by the subtracting wheel of highest denominational order operable to effect a selection of said sub-total taking control means, means operable by said sub-total taking control means to initiate a sub-total taking cycle, and means operable at the beginning of a sub-total taking cycle in which the sub-total is negative to cause insertion of a fugitive one into the lowest denominational order subtracting wheel and of a unit into such higher orders as is necessary, and during the same cycle subsequent to the completion of the sub-total taking to remove the fugitive one from the lowest denominational order subtracting wheel and a unit from each higher order wheel in which such unit was inserted at the beginning of the said sub-total taking cycle.
